UNITED STATES PATENT OFFICE.

DAVID B. YOUNG, OF LAWRENCEVILLE, ILLINOIS.

TANK-CAR VALVE.

Application filed November 21, 1924. Serial No. 751,349.

This invention relates to tank car valves and has for its object to provide a simple, practical and durable construction, capable of installation in a standard tank or equipment with but minor alterations to the latter.

The invention further contemplates a construction wherein liability of leakage through the valve is reduced to a minimum even in the event of a fracture or breakage of the valve parts, the construction embodying the further advantage of being practically thief proof.

Another feature of the herein described construction consists in the provision of automatically compressible packing associated with the valve which permits a ready operation of the valve and insures a tight fit of the valve in closed position.

Other advantages and features of construction will appear more fully as this description proceeds especially when considered in connection with the accompanying drawing, wherein

Figure 1 is a vertical sectional view partly in elevation of a valve constructed in accordance with my invention, a portion of the tank car being illustrated to show the relative position of the valve thereto.

Figure 2 is a horizontal sectional view taken substantially on the plane indicated by the line 2—2 in Figure 1.

Figure 3 is a horizontal sectional view taken substantially on the plane indicated by the line 3—3 in Figure 1.

Figure 4 is a separate sectional perspective view of the valve sleeve assembly; and

Fig. 5 is a fragmentary vertical sectional view similar to Fig. 1 showing a slightly modified form of outlet leg.

Referring now more particularly to the drawings wherein reference characters designate like parts, it will be noted that a portion of a tank car 10 is illustrated, the bottom 11 of which is provided with an outlet 12 to be controlled by the herein described valve. In the upper portion 12 of the tank car—there is mounted a bracket 13 which guidingly supports a valve operating stem or rod 14, provided with a hand wheel 15. The main valve stem 16 is connected to the rod 14 by a knuckle joint 17, thus eliminating side strains and stresses which might otherwise be imparted to the valve bonnet, yet to be described with which the stem 16 engages.

This improved valve assembly can be as-

sociated with and built into the standard outlet leg 18 of the tank car, merely by properly machining the upper part of the leg to receive it.

The valve assembly includes a valve bonnet 19 provided with a plurality of ports 20, and threadedly engages the upper end of the outlet leg 18, as indicated at 21. The threaded portion 22 of the stem 16 passes through the upper end of the bonnet 19 so that a rotation of the stem 16 will cause an operation of the valve sleeve, yet to be described.

A valve sleeve 23 is mounted for reciprocation within the outlet leg 18 and the bonnet 19 and is provided with a plurality of ports 24 adapted to register with the ports 20 in the open position of the valve. The upper end of the valve sleeve 23 is recessed to receive a nut or cap 25, threaded onto the end of the stem 16 and secured thereto by a pin 26. The upper end of the sleeve 23 is also reduced to form a shoulder which is threaded for engagement by a cap 27, which bears against the nut or cap 25, thus connecting the stem 16 to the valve sleeve 23.

The cap 27 is provided with a circumferential shoulder 28 which is adapted to engage an annular extension 29 formed on a gland member 30, the gland member 30 being shouldered to produce the extension 29. The gland member 30 engages in turn, a plurality of packing rings 31 surrounding the valve sleeve 23 and resting in a recess formed in the outlet leg 18.

Obviously, when the valve is operated to raise the sleeve 23, to bring the ports 20 and 24 into registration in the open position of the valve, the shoulder 28 formed on the cap member 27 is moved away from the gland member 30 and pressure is relieved from off the packing rings 31. Consequently, the valve may be opened easily, the freedom of the packing rings and gland, during the opening of the valve permitting the same to operate with facility. As the valve is moved into closed position, the shoulder will engage the circumferential extension 29 on the gland 30 and thus displace the same to compress the packing rings 31, thus preventing the escape of the tank car contents along the sleeve. The shoulder 28 together with the gland member 30 also constitute an auxiliary valve which when the parts are in the positions shown in Fig. 1, will assist in preventing the flow of the oil or other liquid from

the tank car into the outlet leg, as will be readily understood.

It will be noted that inasmuch as the valve bonnet 19 and its connection with the stem 16 are contained within the tank car, that an element of protection is afforded with the result that even though the outlet leg 18 becomes broken, the valve will not become unseated and the contents of the tank car may be preserved. That is to say, it frequently happens in actual practice, in cases of derailment of tank cars that the outlet legs such as 18 are broken off intermediate their ends or in some cases, they are completely torn from the car, in which event the portions of the tank immediately surrounding the outlet valve is so distorted that the valve is either unseated entirely or it leaks to such an extent that some or all of the contents of the car are lost. In order to prevent the tearing of the outlet leg from the car under these conditions, and to insure in the case of accident that it will fracture intermediate its ends, in many instances these legs are provided with circumferential grooves at suitable points which so weaken the walls of the legs that in the event that contact with the ties, rails, or other portions of the road bed, in the event of derailment of a car, they will break or fracture at these weakened points. In the present case, such fracture rings 35 may be provided if desired, see Fig. 5, although they are not believed to be essential since it has been found that outlet legs such as those shown usually fracture at a point 36 adjacent the port holes 24. Also that the valve sleeves themselves will break at these port holes since it is at this point that the valve sleeve contains the least metal and therefore, is the weakest; but even in such a case, the solid upper part of the sleeve 23 will be held seated by the engagement of the stem 16 with the valve bonnet 19. If desired the valve sleeve 23 may be provided with a fracture ring or groove 37 upon its interior surface above the port holes 24 but in view of the weakness of the said ring at the said port holes, it is not deemed necessary that such fracture ring be made.

The structure herein described is of a relatively simple design, thus offering the possibility of economy in manufacture and assembly. Furthermore, as has been hereinbefore mentioned, the construction of this valve adapts it for use in connection with the outlet legs, now standard equipment on tank cars.

While one embodiment of the invention has been described and illustrated herein

in some detail, it will be readily understood that various modifications of this structure may be resorted to without departing from the spirit of my invention and to this end reservation is made to make such changes as may come within the purview of the accompanying claims.

Having thus described my invention, what I claim is:

1. In an outlet valve for tank cars, an outlet leg having a smooth bore adapted to be secured on the exterior of the car, said leg having a fracturable portion intermediate its ends; a hollow valve sleeve freely longitudinally slidable within said bore, provided with a solid head and with ports in its walls beneath said head, said head in the closed position of the valve occupying a position within said leg above said fracturable portion, and said ports occupying positions opposite said fracturable portion; and means for moving said sleeve to bring said ports into and out of said leg.

2. A tank car valve for use in connection with a tank car provided with an outlet leg comprising a bonnet threaded into a recess formed on the upper end of said leg, a valve sleeve mounted for reciprocation within said outlet leg and bonnet, a valve stem secured to said sleeve and threadedly engaging said bonnet for reciprocating said valve sleeve, said valve sleeve and bonnet being provided with ports adapted to register in the open position of the valve, said outlet leg being further recessed to receive a packing gland and rings arranged around said sleeve, and a projection formed on said valve sleeve and engaging said gland for compressing said packing in the closed position of said valve.

3: An outlet valve for tank cars comprising in combination an outlet leg for said car having a bore and a counterbore; a valve sleeve having ports in the walls thereof, slidably mounted in the bore of said leg; compressible packing in said counterbore; a gland in said counterbore above said packing; a valve bonnet having openings in its walls adapted to register with said sleeve ports when the valve is open, one end of said bonnet entering said counterbore and retaining said gland therein; and means carried by said sleeve provided with a shoulder adapted to engage said gland to compress said packing when said valve is closed, said shoulder serving when in engagement with said gland as an auxiliary valve.

In testimony whereof I affix my signature.

DAVID B. YOUNG.
